ABSTRACT: This disclosure describes a package which includes a flexible bag having an open end. A relatively rigid collar is affixed to the bag adjacent the opening in the bag. The bag can be closed by turning of the collar to twist the region of the bag adjacent the opening. The collar is then retained in position with the end of the bag twisted shut.

PACKAGE FOR ARTICLE SUCH AS FRANKFURTERS

Numerous products including food products are packages at the manufacturer's plant in thin plastic or cellophane packages. The packages are typically closed by adhesives or by heat sealing.

As the package is tightly sealed, it is necessary for the consumer to break the plastic or cellophane to open the package. Typically, the product within the package is not completely used by the consumer immediately following opening of the package, and therefore, it is necessary for the consumer to store the unused portion of the product in the broken package. Storage in open and unsealed packages is particularly undesirable for food products or other spoilable or easily contaminable products.

The present invention provides a simple, inexpensive package which is reusable for the life of the product contained therein. The package can be opened without destroying or breaking the walls of the package and it can be easily and tightly closed after the initial opening thereof.

The present invention teaches that these desirable results can be accomplished by providing a bag having an opening therein and affixing a relatively rigid collar to the bag adjacent the rim of the opening. The opening in the collar should be in registry with the opening in the bag. In use, the bag should not be completely filled with product. Rather, the product should terminate short of the opening in the bag, so that a region of the bag projects beyond the end of the product. This region of the bag should be sufficiently flexible to permit twisting thereof. The collar is attached to this region of the bag.

To close the bag, the user turns the collar relative to the main portion of the bag. This twists the flexible region of the bag into a generally hourglass configuration and such twisting results in closure of the bag.

The collar provides a very tight closure for the open end of the bag. When the collar is turned, the twisting of the bag occurs intermediate the product and the outer end of the bag which is attached to the collar. Thus, the open end of the bag is not only twisted closed but is covered by two layers of the bag.

The bag can be retained in the closed position in many different ways. For example, the collar can be bonded to the main portion of the bag and the bond may be of a chemical or mechanical nature. Alternatively, the collar may be taped to the main portion of the bag by pressure-sensitive adhesive tape or it may be secured to the bag by frangible means.

In a preferred form of the invention, however, the collar is sized to fit over the bag and to be frictionally retained thereby. The use of friction to retain the collar in position is preferred because the bag can be easily opened merely by overcoming the force of friction and without the danger of fracturing the thin walls of the bag.

In a preferred form of the invention, the entire bag is constructed of substantially flexible material such as plastic or cellophane. In this event, the product within the bag serves to retain the walls thereof against substantial radial collapse. Thus, the product within the bag cooperates with the collar to provide the necessary frictional force to retain the collar in position. Of course, the bag can be opened by merely counter-rotating the collar to untwist the flexible region of the bag.

The collar serves some additional important functions. First, because the collar is preferably at least somewhat rigid, it holds the open end of the bag fully open to facilitate insertion and removal of the product. Secondly, after the bag is open, it serves as manual means to peel back the open end of the bag for maximum access to the product.

The invention, both as to its organization and method of operation together with further features and advantages thereof may best be understood by reference to the following description taken in connection with the accompanying drawing in which:

FIG. 1 is an elevational view partially in section illustrating a package constructed in accordance with the teachings of this invention and having a product therein with the package being illustrated in the open position;

FIG. 2 is a view similar to FIG. 1 after the collar has been given an initial turn to commence closing of the bag;

FIG. 3 is a fragmentary view similar to FIG. 1 with the bag in the fully closed position and with an end closure member affixed to the outer end of the collar;

FIG. 4 is a view similar to FIG. 1 illustrating the use of the collar in peeling back the open end of the bag from the product contained therein; and

FIG. 5 is a fragmentary perspective view of a second embodiment of the invention with the package being illustrated in the closed position.

Referring to the drawings and in particular to FIG. 1 thereof, reference numeral 11 designates a package constructed in accordance with the teachings of this invention.

Generally, the package 11 includes a flexible bag 13 and a relatively rigid collar 15 affixed to the bag and surrounding an outer portion of the bag. In the embodiment illustrated, the bag 13 contains a product in the form of a plurality of frankfurters 17, although it may be used to contain many different kinds of products.

The bag 13 is preferably constructed of a film plastic such as polyethylene or other materials such as cellophane. Seran wrap, etc. The material from which the bag 13 is constructed is preferably flexible to thereby make the entire bag 13 flexible, although as explained more fully hereinbelow, only a portion of the bag must be flexible.

Although the bag 13 may assume various configurations, in the embodiment illustrated the bag is elongated and has a generally cylindrical peripheral wall 19 and a generally circular end wall 21. The bag 13 is preferably integral and may be constructed in accordance with any known methods. The peripheral wall 19 and the end wall 21 retain the product 17 within the bag 13 as shown in FIG. 1.

The bag 13 has an open end 23 which is opposite the end wall 21. As shown in FIG. 1, a region 25 of the bag 13 projects axially beyond the outer end 27 of the product 17 and a portion 28 of the bag immediately surrounds the product 17. An annular section 29 of the bag 13 immediately surrounding the open end 23 is attached to an annular outer section 31 of the collar 15 by any suitable means such as an adhesive or a heat seal. As shown in FIG. 1, the sections 29 and 31 have considerably shorter axial lengths than does the region 25 of the bag 13.

The sleeve 15 has an axial length which exceeds the axial length of the region 25. The sleeve 15 is preferably at least somewhat rigid and may be constructed of a variety of materials such as cardboard or a plastic material. The sleeve has an inner surface 32 defining an opening or passage 32a which extends completely through the sleeve. As shown in FIG. 1, the sleeve 15 is sufficiently long to be attached at the outer section 31 thereof to the outer section 29 of the bag 13 while an inner section 33 of the sleeve surrounds the bag 13 and the outer end portion of the product 17. In the embodiment illustrated, the sleeve 15 is attached to the bag 13 along the inner surface 32. The sleeve 15 is unattached to the bag 13 except at the section 31 thereof.

It is important that the region 25 have sufficient axial length so that it can be twisted to completely and tightly close the open end 23 of the bag 13 while the section 29 thereof remains firmly attached to the section 31 of the sleeve 15. The region 25 except for the section 29 is the part of the bag that is to be twisted, and therefore, it is only this part of the bag that must be sufficiently flexible to permit twisting thereof. In actual practice of the invention, however, in many instances, it will be most expedient to construct the entire bag 13 of the same material. Furthermore, many of the materials now in use for packaging products of this type employ thin flexible materials such as plastics. For these reasons, the bag 13 is preferably entirely constructed of flexible material.

To close the open end 23, the user grasps the sleeve 15 and turns the latter about its longitudinal axis in either direction relative to the portion of the bag which is immediately confining the product 17. As the outer section 29 of the bag 13 is af-

fixed to the outer section 31 of the sleeve 15, the section 29 turns with the sleeve. The inner end of the region 25 is held against substantial turning movement and thus, the region 25 is twisted to form the generally hourglass configuration shown in FIG. 2. Turning of the sleeve 15 continues until the region 25 is tightly twisted to completely close the open end 23 of the bag 13 as shown in FIG. 3.

As shown in FIG. 3, 25 has been converted into an inner end wall 35 covering the outer end 27 of the product 17, a tight twist portion 37 located centrally of the end wall 35, and an outer end wall 39. Thus, the region 25 has been converted into a double layer closure for the open end 23 of the bag 13. Although the end walls 35 and 37 are slightly axially spaced in FIG. 3, they may be in tight engagement with each other by merely sliding of the sleeve 15 axially inwardly to thereby move the end wall 39 into engagement with the end wall 15. If desired, the end 23 of the bag may be further sealed by an end closure member 41 which may be suitably secured, as by an adhesive or heat seal, to the outer end of the sleeve 15.

The sleeve 15 may be retained in the position shown in FIG. 3 by securing of the sleeve to the bag at some region thereof other than the region 25. Such securing may take the form of pressure-sensitive adhesive tape, fracturable means or a chemical or mechanical bond. In the embodiment illustrated, 25 however, the sleeve 15 is retained in the closed position of FIG. 3 by the force of friction between the inner surface 32 thereof and the portion 28 of the bag 13. Because the bag 13 is entirely flexible, the product 17 holds the bag against radial inward collapse. Thus, the product 17 cooperates with the bag 30 13 to provide the necessary frictional contact between the sleeve 15 of the bag 13. Of course, the force of friction between the bag 13 and the sleeve 15 may be supplemented, if desired, by any other suitable securing means.

The package 11 may be purchased by the consumer in the form shown in FIG. 3. When it is desired to utilize some of the product 17, the consumer counterrotates the sleeve 15 relative to the portion 28 of the bag 13 to untwist the region 25. The end closure member 41, if one has been provided, can then be forcibly removed from the outer end of the sleeve 15 to provide access through the open end 23 of the product 17. The sleeve 15 can then be moved axially inwardly as shown in FIG. 4 to peel back the bag 13 to expose the product 17.

Assuming that less than the full quantity of the product 17 is utilized initially the bag 13 can be closed by first moving the sleeve 15 axially outwardly to the position shown in FIG. 1 and then rotating the sleeve 15 as shown in FIGS. 2 and 3. As the bag 13 is flexible and some of the product 17 has been removed, the circumference thereof will now be insufficient to cause tight frictional engagement between the sleeve 15 and the bag 13. However, as the flexible region 25 of the bag 13 has very little tendency to recover, i.e. it is nonresilient, counterrotation of the sleeve 15 can be prevented by merely laying the package 11 on its side so that it rests upon the peripheral wall 19 and the sleeve 15. Frictional engagement between the sleeve 15 and its supporting surface will then be sufficient to prevent inadvertent opening of the bag 13.

FIG. 5 illustrates a package 11a which is identical to the package 11 except that the collar is provided in the form of an axially short, relatively rigid ring 43 in lieu of the sleeve 15. Thus, the package 11a includes a bag 13a and the ring 43 with the latter being attached to the open end of the bag in the manner described in connection with FIG. 1. In the closed position, the ring 43 snugly embraces the bag 13a adjacent the outer end 27a of the product 17a contained within the bag. About the only functional difference between the packages 11a and 11 is that with the former it is necessary to move the ring 43 axially slightly following the turning of the bag 13a in order to move the ring to the position shown in FIG. 5 in 70 which it circumscribes the bag 13a adjacent the outer end 27a of the product 17a.

Although the sleeve 15 and the ring 43 are both annular in cross section and generally circular in plan, it should be understood that the concepts of this invention are restricted to

this use of this configuration. Similarly, the bag 13 need not be of the elongated cylindrical form shown.

Although exemplary embodiments of the invention have been shown and described, a many changes, modifications and substitutions may be made by one having ordinary skill in the art without necessarily departing from the spirit and scope of this invention.

We claim:

1. In a package for a product, the combination of: a bag having wall means for confining the product and at least one open end, the region of the bag adjacent said open end being sufficiently flexible to permit twisting thereof, said open end being of sufficient size to permit the product to pass therethrough; said bag receiving the product in a snug fit to provide a support by the product for the bag against inward collapse and to cause a segment of the bag to assume a predetermined cross-sectional configuration; a collar having an opening of sufficient size to permit the product to pass therethrough, said collar being affixed to said region of the bag adjacent said open end; said bag having sufficient length to extend beyond the product in the bag, through the region of the bag adjacent the open end of the bag, a sufficient distance to allow closure of the open end of the bag by twisting of said region of the bag, said region of the bag adjacent the open end being twistable by turning of said collar relative to the product in the bag; and the collar having an opening corresponding to the opening in the bag with the product in the bag and disposed in force fit to the bag to provide a frictional relationship between the bag and the collar in the twisted position of the bag and with the product in the bag.

2. A combination as defined in claim 1 wherein said means includes means releasable without fracturing of said wall means to allow turning of a said collar to untwist said region of the bag adjacent said opening in a direction to open said open end of the bag.

3. A combination as defined in claim 1 wherein said opening in said collar is sized to frictionally engage and circumscribe a section of the bag whereby friction between the bag and the collar retains the collar in said position for closing the bag and whereby additional means are provided on the bag, with the product in the bag, for retaining the bag in twisted position.

4. A combination as defined in claim 1 wherein said means includes means for securing the collar to a substantially untwisted section of the bag.

5. A combination as defined in claim 1 wherein said collar is at least somewhat rigid.

6. In a package for a product, the combination of: a relatively flexible bag having wall means to confine the product and an opening at one end of said wall means through which the product can pass in a snug fit to provide a support for the bag against inward collapse and to cause a segment of the bag to assume a predetermined cross-sectional configuration;

a collar affixed to the wall means at an outer section of the wall means adjacent the opening therein, said collar having an opening therein in general registry with the opening in said wall means, said collar filling over at least a portion of the bag and having force fit with the bag with the product in the bag, said opening in said collar being of sufficient size to permit passage of the product therethrough;

said bag being of sufficient length so that when the product is in the bag a particular region of said wall means of said bag lies intermediate the end of the product and said affixation of said collar to said wall means, said particular region of said wall means having sufficient length to close the opening in the wall means by twisting of said particular region of said wall means, said particular region of said wall means being twistable by turning said collar, the twisting of said particular region by the turning of said

collar causing said opening to be closed by opposite ends of said wall means; and
the collar being provided with an opening corresponding to the opening in the bag, with the product in the bag, to retain the product in the bag by the force of friction when the bag has been twisted.

7. A combination as defined in claim 6 wherein said collar is in the form of a ring, said ring being movable generally axially following the turning thereof to a position in which it circumscribes the bag adjacent one end of the product.

8. A combination as defined in claim 6 wherein said collar is in the form of a sleeve, one end portion of said sleeve being affixed to said wall means at the outer section of the wall means and the other end portion of said sleeve circumscribing a portion of said bag which receives the product therein.

9. A combination as defined in claim 8 including an end closure for closing said one end portion of said sleeve.

10. In a package for a product, the combination of:
wall means defining a relatively flexible bag having an opening therein for receiving the product;
said product providing support for the bag against inward collapse and causing a segment of the bag to assume a predetermined cross-sectional configuration;

said product terminating short of the opening in the bag so that a region of the bag projects beyond the end of the product with a sufficient length to provide for a twisting of this region to a closed position;

5 a collar attached to said region of the flexible bag adjacent the opening in the bag, said collar having an opening therein in general registry with the opening in said bag; and

said collar being turnable to twist said region of the bag to close said opening in said bag with at least a double layer of the wall means, said collar fitting over at least a section of said bag and being retainable thereby, said collar having a force fit on the bag, with the product in the bag, to retain the region of the bag in the twisted condition by friction.

10 11. A combination as defined in claim 10 wherein said collar extends along the bag at the positions where the product is retained in the bag.

20 12. A combination as defined in claim 10 including bonding means for bonding said collar to said bag adjacent the open end of the bag.
